UNITED STATES PATENT OFFICE.

THOMAS R. KENNEDY AND EDWARD J. KING, OF ROCHESTER, NEW YORK,
ASSIGNORS TO THE CO-OPERATIVE FOUNDRY COMPANY, OF ROCHESTER,
NEW YORK, A CORPORATION OF NEW YORK.

DESIGN FOR A STOVE.

SPECIFICATION forming part of Design No. 36,596, dated October 20, 1903.

Application filed July 31, 1903. Serial No. 167,808. Term of patent 7 years.

To all whom it may concern:

Be it known that we, THOMAS R. KENNEDY and EDWARD J. KING, citizens of the United States, residing at Rochester, in the county of Monroe and State of New York, have invented a new, original, and ornamental Design for Stoves, of which the accompanying drawing is a representation.

The figure is a perspective view of a stove, showing our new design.

What we claim as new, and desire to secure by Letters Patent, is—

The ornamental design for a stove as herein shown.

THOMAS R. KENNEDY.
EDWARD J. KING.
